UNITED STATES PATENT OFFICE.

CLARENCE F. PEPPER, OF ST. LOUIS, MISSOURI.

MACHINE FOR STEMMING CURED TOBACCO-LEAVES.

1,235,722.

Specification of Letters Patent.

Patented Aug. 7, 1917.

Application filed July 14, 1916. Serial No. 109,298.

To all whom it may concern:

Be it known that I, CLARENCE F. PEPPER, a citizen of the United States, residing at St. Louis, in the county of St. Louis and State of Missouri, have invented certain new and useful Improvements in Machines for Stemming Cured Tobacco-Leaves; and I do hereby declare the following to be a full, clear, and exact description of the invention, such as will enable others skilled in the art to which it appertains to make and use the same.

This invention is a machine for separating substances, such as separating one part of a vegetable substance from another part thereof. The device is designed more particularly for removing stems from tobacco leaves, although it is obvious that the invention is applicable to other uses.

In the commercial treatment of tobacco it is desirous, under some conditions, to remove the stem from the body of the leaf after the tobacco shall have been cured. To do this by manual labor is slow, tedious work.

A purpose of this invention is to mechanically remove the stems from the tobacco leaves by mechanism which will require merely the attendance of unskilled labor, and thereby effect a saving in time and operating expenses.

Further objects and advantages will become apparent from the following detailed description of the invention, taken in connection with the accompanying drawings and the appended claims.

Broadly stated, the invention comprises an endless carrier associated with a table and compressed air mechanism, whereby the leaves may be fed from the table to suitable gripping devices mounted on the endless carrier to be presented before a blast nozzle which is automatically opened by means on each successive gripping device and directs air under pressure against the leaf or leaves carried by the gripping devices. The lighter portions of the leaves are torn away and carried by the air blast against a screen and therefrom drop into a suitable receptacle, while the heavier and more fibrous portions, such as the stems, are retained firmly by the gripping devices until such devices are engaged by releasing trips, whereupon the gripping devices permit the heavier fibrous portions, such as the stems,

to fall from the carrier. The leaves are merely placed in a predetermined position on the table by unskilled labor; thereafter the leaves are seized or gripped automatically by the gripping devices.

The gripping devices are of novel form comprising spring actuated jaws which are normally retained in their closed positions, but which are opened automatically by contact with trip devices at predetermined points on the passage of the gripping device across the table.

To enable others to more clearly understand the invention, a practical form of the device is illustrated in the accompanying drawings, but it is to be understood that the construction therein shown is for the purposes of illustration only, and not as defining the limits of the invention.

In the drawings:

Figure 1 is a side elevation of a device embodying the invention.

Fig. 2 is a plan view of the same.

Fig. 3 is a detail view of a gripping device.

Fig. 4 is a detail view, in plan, of the fluid blast nozzle.

Fig. 5 is a detail front view of the cam trip and guide block.

Fig. 6 is a front elevation of the structure of Fig. 5.

Fig. 7 is a detail view of the lower member of the gripping jaw.

Fig. 8 is a detail view of the upper gripping jaw member.

Fig. 9 is a detail front view of the lower trip.

Fig. 10 is an end view of the lower trip.

Referring more particularly to the embodiment of the invention illustrated in the drawings, the table 1 may be of any desired form or material, and is preferably provided with a trough indicated at 2 to insure the feeding of the substance to be treated, such as leaves, at the proper position to be engaged by the gripping devices.

Suitably mounted on the table 1 is an endless carrier 3, which may be of any desired form or material, such as a chain, and is shown passing over a plurality of pulleys 4, 5, the pulley 4 being shown mounted on a shaft 6 having the usual power wheel or drum 7. If desired, the endless carrier may be provided with guide plates 8, mounted from the table 1 by bracket arms 9 to sup-

port the carrier and prevent it from sagging due to its own weight and the weight of the load it carries.

Positioned adjacent the upper lead of the endless carrier is shown a guide block 10 of any suitable form which may be mounted in any preferred manner from the table 1. This block 10 is designed to guide the carrier so that its gripping devices indicated at 10 11 may be brought into contact with an adjacent trip member 12, shown in the form of a cam, which is designed to engage a grip device 11 and open its jaws previously to the device 11 reaching the trough 2 and to 15 permit the jaws of the device 11 to close into gripping engagement with material fed into the trough 2 for the purpose of conveying such material away from the table. The cam trip device 12 may be of any desired form and mounted in any suitable manner adjacent the table 1 and guide block 10, such as by means of the bracket arm 13.

The grip device is shown as comprising 25 a plurality of members 14, 15 pivotally connected, as at 16. The member 14 is provided with a jaw 17 adapted to coöperate with a similar jaw 18 of the member 15. One member 14 is shown provided with a plurality of flanges 19 which provide a channel 20 between them, and into this channel operates a rib 21, which is shown rounded on its face, carried by member 15. The pivotal connection 16 may be in the form of a pin 30 which passes through the flanges 19 and rib 21 to permit the members to have rocking engagement relative to one another. Any suitable means, such as the resilient element 22 may be employed to maintain the 35 jaws 17, 18 in their closed positions. The jaws preferably have broad engaging ends to enable them to seize a plurality of leaves or stems at each gripping operation. If desired, one member, such as 15, may be 40 provided with a guide notch 23 to be engaged by the cam trip 12 to insure movement of jaw 18 relative to jaw 17.

The gripping device 11 is shown mounted diagonally across the endless carrier 3 with 45 its jaws 17, 18 positioned in the direction of travel, or in advance of the rear portion of the device 11. Owing to this angularity of the mounting of the device, it may be found desirable to employ an additional 50 guide block 10^a, shown in substantially vertical alinement with the table trough 2. The guide block 10 engages the under face of the grip member 14 near its end 24 at substantially the same time that guide block 55 10^a is engaging the under surface of the same member 14 near the jaw 17. This provides a plurality of supports for the grip device 11 when the cam 12 engages the outer end of member 15 at the guide notch 23.

60 Guide blocks 10 and 10^a, and cam 12, being

rigidly mounted on the table, the grip device will be deflected on the endless carrier until cam 12 engages the notch 23, when the grip device 11 will be prevented from further deflected movement on the endless carrier, thereby permitting cam 12 to ride over the end of the grip device at 23. This action serves to move member 15 on its pivot 16 to separate jaw 18 from jaw 17 at the moment the jaws 17, 18 are riding over a portion of guide block 10^a ready to seize material fed into trough 2 when the end 23 shall have passed the cam 12. The resilient element 22 is preferably positioned between the ends 23 and 24 of the members 14 and 15, thereby leaving that portion of the grip device between the pivot 16 and jaws 17, 18 unobstructed, to permit of the passage therebetween of a jaw separating cam 30.

Near one end of the table 1 there is shown 75 suitable means to separate the stem from the body of the leaf. The separating means may be in the form of a compressed air tank 24^a supplied with air under pressure from a suitable source, and having a directing 80 nozzle 25 of any suitable form controlled by a valve 26. The valve is preferably 85 spring actuated to maintain the valve in its closed position, but is shown provided with an actuating arm 27 adapted to be engaged 90 by a wiper arm 28 mounted on a grip device 11, so that the air valve 26 will be opened to permit air under pressure to escape as the carrier 3 brings the grip device 11 with its load opposite to the nozzle 100 25. The pressure of air will tear away the body of the leaf from the stem, leaving the stem with the grip device and conducting the remaining portion of the leaf to a suitable receptacle, not shown. If desired, a 105 screen 29 may be employed to prevent the escape of the separated leaf portions.

In order that the grip devices 11 may be 110 ready to seize another load from the trough 2, it is desired to automatically free them 115 of the stems which they hold after passing before the nozzle 25. This is accomplished by providing a suitable trip 30, shown mounted on the table 1 adjacent the lower lead of the carrier 3. This trip 30 may be 120 of any desired form and material, but is shown oval and is so positioned that it will separate the jaws 17, 18 to permit the leaf stem to fall into a suitable receptacle (not shown) when the trip 30 passes through the 125 space formed between the jaws 17 and 18 and in advance of the pivot 16.

If desired, the stem in the grip device may be turned to a predetermined position by contacting the stem against a leg *x* of 125 the table 1, whereby the stems may be deposited in an orderly manner in substantially the same direction in any suitable container, not shown.

It is obvious that various changes in the 130

form and proportions of parts may be made without departing from the spirit of the invention, and the right is reserved to make such changes and alterations as fairly fall 5 within the scope of the appended claims.

Having thus fully described the invention, what I claim is:

1. In a device of the class described, a 10 table, an endless carrier coöperating therewith, a gripping device mounted on the carrier, a blast nozzle in coöperative relation to the carrier, said nozzle having a control valve provided with a pivoted actuating arm, means to supply air under pressure to 15 the nozzle, and an arm projecting from the gripping device to move the valve arm on its pivot to open the valve when the gripping device is adjacent the nozzle.

2. In a device of the class described, a 20 table, an endless carrier coöperating therewith, gripping devices mounted on the carrier and each provided with a wiper arm, a fluid nozzle having a valve provided with an actuating arm, and resilient means to retain 25 the actuating arm in a predetermined position to close the valve, said actuating arm being positioned in the path of the wiper arms of the gripping devices whereby the valve of the fluid nozzle may be opened during 30 the passage of the gripping devices adjacent thereto.

3. In a device of the class described, a 35 table having a trip device including a guide block and a cam block positioned adjacent to and coöperating with the guide block, and an endless carrier having gripping devices each provided with a plurality of pivotally connected jaws, means to maintain the jaws in a closed position, one of said jaws 40 being arranged to ride in the guide block to be held in a non-pivoting position while the other jaw is being engaged by the cam block to separate the jaws.

4. In a device of the class described, a 45 table, an endless carrier, a gripping device mounted on the carrier, said device having a plurality of pivotally connected members having coöperating jaws, resilient means to maintain the jaws in their closed position, 50 one of said pivoted members having a guide notch near its end opposite its jaw, a guide

block carried by the table to support the gripping device when passing over the block, and a cam trip mounted substantially opposite to the guide block to engage the 55 guide notch and ride over its member to move the notched end of one pivoted member toward the corresponding end of the other pivoted member when engaged by the guide block, and thereby separate the jaws 60 against the energy of the resilient means.

5. In a device of the class described, a 65 table, an endless carrier, a gripping device mounted on the carrier, said device having a plurality of pivotally connected members having coöperating jaws, resilient means to maintain the jaws in their closed position, one of said pivoted members having a guide notch near its end opposite its jaw, a plurality 70 of guide blocks arranged in spaced relation from the table to permit a lead of the endless carrier to move between them, said guide blocks serving to simultaneously support one member of a gripping device at a plurality of points when passing over said 75 blocks, and a trip mounted in coöperative relation to the guide blocks to engage the guide notch of the other pivoted member and ride over this member while the gripping device is between said trip and the 80 guide blocks, to separate the jaws of the gripping device.

6. In a device of the class described, a 85 table, an endless carrier mounted adjacent thereto, means to convey material in a predetermined position on the carrier, means to remove a portion of such material from the conveyer means, a leg of the table being positioned in coöperative relation to the endless carrier, whereby when the leg of the 90 table engages the remaining portion of the conveyed material, it will serve to move the material so conveyed to a predetermined position, and means to discharge the material from the conveying means at a predetermined point, whereby the material may be deposited in an orderly manner.

In testimony whereof, I affix my signature, in presence of a witness.

CLARENCE F. PEPER.

Witness:

A. L. HOUGH.
